CAR FRAME

Application filed February 27, 1928. Serial No. 257,428.

This invention relates to improvements in fabricated steel structures, and more particularly to structural frames used in locomotive tenders, although, as will hereinafter appear, 5 the invention is not necessarily limited to such use.

Locomotive tender frames have heretofore been made up of many pieces bolted and riveted together, while more recently such frames have been made in integral or one 10 piece castings. However, it has been found that as the size of tenders and their frames increased the one piece steel tender frame castings have become somewhat too heavy 15 and unwieldy to be readily moulded.

We find it desirable to form the end frame members only, which include the bolsters and adjacent end sills, of integral castings, and connect such end frame members together by 20 relatively light structural steel sills. This latter type of construction affords a very substantial saving in the cost of relatively long tender frames and furthermore, lends itself to standardization far more than the one 25 piece casting, inasmuch as any reasonable length of frame can be constructed by simply varying the length of the connecting sills.

Our present invention consists broadly in 30 providing integral end frame castings connected together by lighter structural steel sills, as above described, and more specifically relates to improvements in methods for connecting castings to the structural steel member by autogenous welding so as to overcome the difficulties heretofore encountered, 35 on the one hand, by ordinary riveted connections, and on the other hand, by ordinary welding methods, which are especially liable 40 to give unsatisfactory results where relatively light formed or rolled steel sections are welded to heavier cast steel sections. Accordingly, in the present invention we utilize an improved form or type of welded connections, 45 having as their chief characteristic that the

weld is so disposed as to be in compression or shear, rather than tension, in a direction longitudinal of the connecting sills or beams, so that the weld will be able to develop or maintain substantially normal strength even 50 though, as sometimes occurs, it is not of the highest degree of workmanship.

It will be seen further that our improved forms of welded connections are particularly adapted for use in tender frame constructions 55 such as herein contemplated, but is also capable of wide application over other forms of fabricated steel structures.

The invention may best be understood by reference to the accompanying drawings, in 60 which

Figure 1 is a plan view of a tender frame made up of integral end frame members joined together by intermediate connecting sills in accordance with our invention. 65

Figure 2 is a side view of the frame shown in Figure 1.

Figure 3 is an enlarged section taken on line 3—3 of Figure 1.

Figure 4 is an enlarged fragmentary section of the form of sill shown in Figure 1, showing details of a preferred form of welded joint between the end frame and the central connecting sills. 70

Figure 5 is a sectional view taken on line 75 5—5 of Figure 4.

Figure 6 is a section taken on line 6—6 of Figure 5.

Figure 7 is a plan view of a modified form 80 of joint somewhat similar to that shown in Figure 4.

Figure 8 is a side view of the joint shown in Figure 7.

Figures 9 and 10 are top and side views 85 of a preferred form of welded joint in which two sills formed of H-beam sections are utilized.

Figures 11 and 12 are top and side views 90 respectively of still another form of welded

section employing a single H-beam section as the center sill.

Figure 13 is a plan view of another form of welded joint for connecting the end frame to a single centrally disposed sill formed of an H-beam section.

Figure 14 is a side view of the frame shown in Figure 13.

Figure 15 shows another form of welded connection for double center sills formed of two channel-beam sections.

Figure 16 is a side view of the connections shown in Figure 15.

Figure 17 is an enlarged sectional view taken on line 17—17 of Figure 8.

Figure 18 is an enlarged sectional view taken on line 18—18 of Figure 9.

Figures 19 and 20 are top and side views respectively of a welded joint suitable for a bolster and side sill, utilizing our improved form of welded joint.

Figure 21 is a section taken on line 21—21 of Figure 19.

Figures 22 and 23 are sections showing modified forms somewhat similar to Figure 21, wherein the side sill consists of an inwardly turned channel member.

Figure 24 is a modified section somewhat similar to Figure 21, but wherein the side sill consists of an outwardly turned channel member.

Referring now to details shown in the drawings, Figures 1, 2 and 3 show a tender frame which is made up of two end frames indicated generally at 10 and 11, and separate connecting means therefor herein including a pair of longitudinal center sills 12, 12 and side sills 13, 13. Intermediate transverse supports 14, 14 may also be provided.

Each of the end frame members includes end sill 15 and bolster 16 connected by a center member 17 carrying draft connections of suitable construction, all being formed in an integral casting. The center connecting sills 12, 12 and side sills 13, 13 are preferably of standard structural steel forms, as shown herein, the center sills being of H-beam construction, while the side sills 13 are of channel sections. The center sills 12, 12 are suitably secured to inwardly projecting supports 18, 18 carried by the end frame members 10 and 11.

While our invention broadly includes the use of rivets for connecting the sills to the end frames, as indicated at 20, 20 in Figures 5 and 8, we prefer to utilize an improved form of welded joint, inasmuch as it is found that the enormous stresses set up at these points of juncture due to constant pulling and buffing transmitted through the draft gear, (of which the longitudinal sills form a part) is likely in time to loosen any ordinary riveted connections, with an ultimate tendency to shear the rivets. Accordingly, in the pre-

ferred forms shown in most of the detailed figures herein, we utilize an improved form of welded joints.

One form of welded joint which is particularly adapted for joining center sills 12, 12 with end frame member 10 is shown in detail in Figures 4, 5 and 6. In this form the longitudinally projecting supports 18, 18 carried by the end frame each have their outer faces 25 shaped to fit against the upright web 26, and between the upper and lower flanges 27 and 28 of the I-beam sections 12. A plurality of bosses 30, 30 (herein in a double row) are formed on the outer face of wall 25 and projecting through apertures 31 formed in the web 26 of each sill 12. The joint thus made is welded together about the lugs 30, as indicated at 32, so as to produce a homogeneous structure in continuous lines about each one of the lugs 30. As will be seen in Figure 6, this form of joint is extremely strong inasmuch as it is capable of resisting all stresses in a direction longitudinally of the beams 12, or transversely of the lugs 30, without imposing undue stress upon the welded portions of such joint, since the welded connections are under compression or shear on the side from which pressure is applied, so that the joint will be secure even though the lines of weld crack about one or more of the lugs, as is often the case with welded joints, even though done in the most careful manner, and especially where, as here, the two pieces being welded are of different thicknesses and physical properties so as to be especially subject to warping or cracking after they have cooled.

It will therefore appear that the welded joints about lugs 30, 30 are designed to carry the major portion of the load. Other welding may also be utilized to provide additional strength to the joint, as for instance, by lines of welding 36, 36 along upstanding flanges 35, 35 carried on supports 18 adjacent the edge of upper and lower flanges 27 and 28 of the sill 12 and also continued along the inner end of said flanges where they abut the bolster 16. A further line of welding 37 may also be provided along the extreme end of web 26 where it abuts the end frame casting 10, as is best shown in Figure 5. It will be noted that in the form shown in Figures 4 and 5 the upper and lower flanges 27 and 28 of the sills 12 extend slightly beyond the extreme end of upright web 26 so as to form an interlocking connection with the end frame 10 in a vertical direction.

In the modified forms shown in Figures 7, 8 and 17, a plurality of bosses 30^a, 30^a are carried on the upright wall of longitudinal supports 18 as before, but in this instance the bosses are somewhat larger and disposed in a single row. In this form also the ends of upper and lower flanges 27^a and 28^a are flush with the extreme end of the upright web 26

of sill 12, instead of projecting beyond the end of the latter, as in the form shown in Figures 4 and 5. In addition, the support 18 is provided with a series of lugs 38, 38 which fit in recesses 39, 39 formed along the inner margin of the upper and lower margin 27^a and 28^a and a line of welding 36^a follows along the the cooperating lugs and recess 38 and 39 respectively. The joint formed along the latter lugs and recess therefore partake of similar characteristics to the joint formed about lugs 30^a, 30^a, namely, the welded joints are in compression or shear against stresses in either direction longitudinal of the sills 12.

In the form shown in Figures 9, 10 and 18 a plurality of bosses 30^a, 30^a are provided, somewhat similar to that just described but carried on opposite sides of a single centrally disposed supporting projection 18^a. In this form a pair of continuous upstanding flanges 35^a, 35^a are provided along the entire length and at opposite sides of the central supporting projection 18^a.

Figures 11 and 12 show a simple adaptation of an improved welded joint to a construction wherein a single I-beam section 12^a is utilized for a center sill. In this form a weld is made along line 40 where the end of beam 12^a abuts the end frame 10 and the joint is further reinforced by a pair of plates 41, 41 which overlap upper and lower surfaces of the beam 12^a and end frame 10 adjacent the weld 40, said plates having apertures therethrough for engagement by interlocking lugs 43 and 43^a upstanding on the parts 10 and 12^a, respectively, and welded as before, said plates also being welded to both parts around their margins, as indicated at 42, 42.

In the form shown in Figures 13 and 14, a single H-beam section 12^a is provided with a web portion 26^a forming a part of vertical web but projecting beyond the ends of upper and lower flanges 27 and 28. The portion 26^a is provided with a pair of oppositely disposed recesses 44, 44 in which lugs 45, 45 carried by the main frame 10 are adapted to fit. A pair of plates 41, 41 having apertures for interlocking lugs 43, 43^a are also provided on top and bottom of the beam, as in the case of the form shown in Figures 11 and 12. A line of welding 46 also follows along the line of juncture of lugs 45 and recesses 44, so as to provide additional strength against longitudinal shearing stresses.

In the form shown in Figures 15 and 16, a somewhat similar arrangement is applied to a pair of channel sections 12^b—12^b with which lugs 45^a are provided on the inner sides of a bifurcated support 10^a carried by the end frame 10. These lugs 45^a fit in apertures 44^a formed in the vertical web of beam 12^b.

A similar form of welded joint is also adapted for use in connecting the ends of

bolsters 16, 16 to the side sills 13. Certain forms of such welded joints are suggested in Figures 19 to 24, both inclusive. In the form shown in Figures 19, 20 and 21 the ends of the bolster 16 are arranged to fit within the side sills 13, which, in the form shown, have an inwardly turned channel section. Lugs 30^b are carried on the ends of bolster 16 and project through circular recesses 31^b formed in the side sills 13 and are welded thereto by lines of welding 32^b. Another line of welding 50 is formed along outward standing flanges 51 on beam 16.

The form shown in Figure 22 is similar to that shown in Figures 19, 20 and 21, excepting that the upstanding flanges 51, 51 are omitted, and the inner marginal edges of the side sill 13 are welded at 50^a flush with the upper and lower surfaces of bolster 16.

In the modified form shown in Figure 23 the construction is substantially similar to that shown in Figure 21 with the exception that upstanding flanges 51^a, 51^a are made of somewhat increased height so as to permit a wedge 52 to be inserted before the parts are welded together.

In the event that an outwardly turned section is utilized by side sill 13, the joint may be completed substantially as shown in Figure 24 in which the side sill 13^b fits between upper and lower flanges 55, 55 carried on the outer end of bolster 16, as shown.

It will now be clear that although the welded form of joint is herein disclosed in connection with a tender frame structure, it can also be applied to a wide variety of uses, especially where lighter sectioned steel parts are welded to heavier sections such as castings or the like.

We claim as our invention:

1. In a car, two end frame members each consisting of an end sill, draft connections and a bolster formed together in an integral casting, and means connecting said end frames comprising longitudinal structural steel beams joined at opposite ends to said end frames by welded joints including transversely extending lugs on the latter in interlocking engagement with said beams, whereby said welded joints are in compression under stresses applied longitudinally of said beams.

2. In a car, two end frame members each consisting of an end sill, draft connections and a bolster formed together in an integral casting, and means connecting said end frames comprising longitudinal structural steel beams joined at opposite ends to said end frames by welded joints including transversely extending lugs on the latter in interlocking engagement with and extending through said beams whereby said welded joints are in compression under stress applied longitudinally of said beams.

3. In a car, two end frame members each

consisting of an end sill, draft connections and a bolster formed together in an integral casting, and means connecting said end frames comprising longitudinal structural steel beams joined at opposite ends to said end frames by welded joints including transversely extending substantially circular lugs on the latter in interlocking engagement with and extending through said beams whereby said welded joints are in compression under stress applied longitudinally of said beams.

Signed at Chicago, Illinois, this 8 day of February, 1928.

15   GEORGE S. GOODWIN.
                      CLARA H. TOLLERTON,
*Executrix of the Estate of William J. Toller-
ton, Deceased.*
